ATTORNEY.

UNITED STATES PATENT OFFICE

BERT BECKER, OF MONROVIA, CALIFORNIA

DESIGN FOR A BOTTLE

Application filed October 21, 1929. Serial No. 33,130. Term of patent 7 years.

To all whom it may concern:

Be it known that I, BERT BECKER, a citizen of the United States, residing at Monrovia, in the county of Los Angeles and State of California, have invented a new, original, and ornamental Design for Bottles, of which the following is a specification, reference being had to the accompanying drawings, forming a part thereof, and wherein—

Fig. 1 is a perspective view of the bottle, which is square, the view being taken looking at a corner of the bottle to develop the diagonal width thereof.

Fig. 2 is a side elevation thereof; and

Fig. 3 is a top plan view.

The dominating feature of the bottle is the contour. The general effect of this contour is that the bottle is decidedly squat as best seen from the perspective view of Fig. 1, while in a true side elevation as seen in Fig. 2 the appearance is somewhat elongated.

A wet or iced appearance is given by means of short irregular lines disposed over the body of the bottle.

I claim:

The ornamental design for a bottle substantially as shown and described.

BERT BECKER.
